The ornamental design for a non-pneumatic tire, as shown and described.

DESCRIPTION

FIG. 1 is a perspective view of a non-pneumatic tire showing our new design; and,

FIG. 2 is a left side view thereof; with the right-side view being identical thereof.

The dash-dash broken lines shown illustrate environmental structure that forms no part of the claimed design. The alternate long and short dash broken lines indicate the boundary between the claimed and unclaimed part.
